UNITED STATES PATENT OFFICE.

WALTER J. BELL, OF LOS ANGELES, CALIFORNIA, ASSIGNOR OF ONE-HALF
TO LEON F. MOSS, OF LOS ANGELES, CALIFORNIA.

CIRCUIT-CLOSER.

SPECIFICATION forming part of Letters Patent No. 727,064, dated May 5, 1903.

Application filed January 2, 1903. Serial No. 137,501. (No model.)

To all whom it may concern:

Be it known that I, WALTER J. BELL, a citizen of the United States, residing at Los Angeles, in the county of Los Angeles and State of California, have invented certain new and useful Improvements in Circuit-Closers, of which the following is a specification, reference being had therein to the accompanying drawings.

10 This invention relates to electric-railway switches, and is directed to an improved circuit-closing mechanism for effecting the energizing of the magnet by which the switch-tongue is thrown, the object of the invention being the production of simply-constructed means capable of attachment to the ordinary trolley-wheel and connections and operating in a reliable manner regardless of inclement weather conditions to close the circuit in which 20 the magnet is located.

The nature of the invention will be readily comprehended, reference being had to the following detailed description and to the accompanying drawings, illustrating the invention 25 in its preferred form, it being understood that various modifications may be made therein without departing from the spirit of the invention as defined by the claims.

In the drawings, Figure 1 is an elevation 30 of a circuit-closer embodying the invention. Fig. 2 is a vertical transverse sectional view. Fig. 3 is a perspective view of a modification.

Referring to the drawings by numerals, 1 denotes the trolley-pole, having at its upper 35 end arms 2 2, in which are bearings for the shaft 3 of the trolley-wheel 4. The feed-wire 5 is supported in the usual manner from an insulating-block 6, which in turn is supported by wires 7 7, one or both of which lead to the 40 switch-throwing magnet. (Not shown.)

8 8 designate rings or disks which flank the trolley-wheel and are insulated therefrom by interposed rings or disks 9 9, of insulating material.

45 10 10 are yielding contact-brushes carried by and insulated from the trolley-pole and from which lead circuit-wires 11 11, in which are located circuit-closers, such as push-but-

tons located on the car, the contacts 10 having a yielding engagement with the disks 8, 50 and said disks are also yieldingly engaged by contacts 12 12, pivoted to the block 6, which, as stated, forms the support for the trolley-wire. The contacts 12 by pivotal connection with the block are acted upon by gravity to 55 engage the disks 8.

In Fig. 3 is shown a modified construction by which a prolonged engagement is made between the upper contacts and the disks 8. A number of blocks 6 are suitably supported 60 and pivotally secured to the blocks, and depending therefrom are arms 14 14, to the lower ends of which are secured contact-bars 15 15, which yieldingly engage the disks 8 as the trolley-wheel passes between them. The 65 bars 15 15 may be made to have any desired length. Surmounting the structure is a hood 16, which extends beyond the ends of the bars. The circuit-wires 7, or one of them, lead from the contacts 12 to the coils of the magnets. 70 The parts are surmounted by a hood 13, supported from the block 6 and serving to protect the contacts from snow and ice, which would tend to clog their action. The circuit-closer being manipulated by the operator on 75 the car, a circuit is established with the motor feed-wire through wire 11, contact 10, disk 8, contact 12, wire 7, and the magnet.

Obviously in the case of right and left hand side tracks separate switch-throwing mechanisms including magnets will be provided and will be controlled through the right and left hand wires 7 7, above described. There will also be on the car right and left hand push-buttons, either one of which is manipulated by the operator, dependent upon the direction the car is to leave the main track.

I claim as my invention—

1. In a circuit-closing mechanism, an insulated trolley-wire support, a trolley-wheel 90 flanked by insulated disks, contacts in engagement with the disks and connected with a controllable circuit on the car, and terminal contacts on said support engaging said disks.

2. In a circuit-closing mechanism, an insu-

lated trolley-wire support, a trolley-wheel flanked by insulated disks, brushes in contact with the disks and connected with a controllable circuit on the car, gravity terminal contacts pivoted to said support and engaging said disks, and a hood covering the support and contacts.

In testimony whereof I affix my signature in presence of two witnesses.

WALTER J. BELL.
